UNITED STATES PATENT OFFICE.

PETER D. PEARCE, OF GRAND RAPIDS, MICHIGAN, ASSIGNOR TO UNION STEEL PRODUCTS COMPANY, LTD., OF ALBION, MICHIGAN, A CORPORATION OF MICHIGAN.

RACK.

Application filed July 29, 1918, Serial No. 247,231. Renewed March 20, 1925.

To all whom it may concern:

Be it known that I, PETER D. PEARCE, a citizen of the United States of America, residing at Grand Rapids, in the county of 5 Kent and State of Michigan, have invented certain new and useful Improvements in Racks; and I do hereby declare the following to be a full, clear, and exact description of the invention, such as will enable others 10 skilled in the art to which it appertains to make and use the same.

This invention relates to a rack, particularly adapted to hold jars or cans for ready immersing in or removal from boiling water 15 in any suitable receptacle in the process of cooking the contents within the jars, said process being known as the "cold pack method." It is an object and purpose of the present invention to provide a simply 20 constructed and economical holder or rack which will contain jars of different sizes and which, when not in use, may be collapsed in a very small compass, this last being of particular advantage when the rack is not 25 used and in shipping the rack to the retailer or customer. The invention consists in novel constructions and arrangements of parts for attaining this end, as well as many others not specifically enumerated at this 30 point, but which will appear as understanding of the invention is had from the following description taken in connection with the accompanying drawing, in which,

Fig. 1 is a plan view of one member of 35 the rack, the same lying in horizontal position.

Fig. 2 is a side elevation of the complete rack, and

Fig. 3 is a plan view of another member 40 of the rack used in conjunction with the first member shown in Fig. 1.

Fig. 4 is an enlarged detailed plan view showing the construction for hinging the 45 bails to the lower frame. Fig. 5 is an enlarged detailed elevation of the same. Fig. 6 is an enlarged detailed sectional view on the line 6—6 of Fig. 3.

Like reference characters refer to like 50 parts in the different views of the drawing.

In construction a base is provided comprising a substantially rectangular frame made from a single length of wire and including parallel sides 1 connected by 55 parallel ends 2. Wires 3 and 4, in spaced apart relation, extend lengthwise of the base

and, similarly, transverse wires 5, in spaced apart relation, are used to complete the base, said longitudinal and transverse wires being soldered together at their crossing points and having soldered connection to the outer frame at their ends. At spaced apart intervals in the lengths of the sides 1 of the frame, U-shaped bends 6 are made to serve as supporting feet to hold the bottom a short distance above any support on which the rack may be placed. Each longitudinal wire 3, as shown in Fig. 1, at each end extends a slight distance beyond each end 2 of the bottom and is formed into a loop 7. A bail is connected at each end of the bottom, the sides 8 thereof being coiled around the loops 7, as indicated at 9, said coils terminating in extensions 10 which are adapted to engage against the upper sides of ends 2 to stop said bails from movement toward each other beyond vertical position, as shown in Fig. 2. When the handles are raised to a perpendicular position and the extensions 10 engage the bottom frame, any tendency to any inward movement of the handles beyond this position will result in placing the coils 9 under tension and the coils will operate to urge the handle members outwardly. The sides 8 extend from the bottom for a distance and are then turned inwardly 85 toward each other making horizontal shoulders 11, the inner ends of the wires forming said shoulders being reversely turned to make substantially U-shaped loops 12, above which the wires forming the bails 90 are extended to make handles 13 which may be readily grasped by the hands for insertion in or removal of the rack from boiling water contained within any suitable receptacle. It will be noted that this construction permits the bails to be turned to vertical position as shown in Fig. 2, or when the rack is not in use, the same may be turned underneath the bottom of the rack and collapsed into a very limited space.

The rack is completed by a second upper member formed of wire and which includes an elongated frame having parallel sides 14 connected by ends 15. On each end, and on the inner side thereof, a wire 16 is disposed in parallel relation to its adjacent end 15, said wire 16 at each end being bent underneath the adjacent wire 15 and soldered thereto. A wire 17 extends lengthwise of the frame, being secured at each end to said 105 110

members 16. In the length of said wires 17, a plurality of spaced apart bends 18 are made whereby a number of seats are provided in the length of the wire and on the 5 under side thereof. This frame is completed by a plurality of cross wires 19 slidably connected at their ends to the sides 14 and passing underneath the central wire 17. It is obvious that the wires 19 may be adjusted to different positions on the frame, the same seating in the seats made by the 10 bends 18 in the central wire 17. This permits the sizes of the compartments in said upper member to be varied to receive jars 15 or cans of different sizes.

The upper rack member is applied to the member first described by inserting the upper ends of the bails between the parts 15 and 16 and then forcing said upper rack 20 member down until it is stopped by the shoulders 11. In practice, in attaching said upper rack member, the wires at each side of the handle 13 are sprung inwardly until the loops 12 are reached, whereupon they return 25 to their original position and the upper rack member is held firmly in place, but may be removed at any time by pressing the wires of the handle 13 toward each other, as will be obvious.

30 A rack thus constructed may contain a large number of jars or cans, which rest on the base and pass upwardly between the various wires 14, 17, and 19 of the upper member of the rack. The handles 13 extend 35 for a considerable distance above the tops of the jars or cans which may be held by the rack so that the rack carrying cans or jars may be entered sufficiently into boiling water in any suitable receptacle to either 40 wholly or partially cover the cans or jars, with the handles 13 at all times extending a distance above the water. When not in use the two members of the rack may be separated and collapsed into small space. This 45 also is of particular advantage in shipment, as the entire rack may be placed in a flat box of not more than one and one-half inches in height. The adjustment of the transverse wires 19 toward or away from 50 each other makes the rack available for all sizes of cans or jars normally used and, by removing the upper member of the rack, the remaining member may be used after the 55 canning season is over as a support for clothes in a wash boiler, the same being readily removed by merely grasping the handles and lifting on the same without the necessity of bringing the hands into contact with the hot water. The rack is made entirely of wire, is very economical to produce, and is of great utility not only to carry out 60 the cold pack process of cooking canned goods, but for the other purposes described.

I claim:

65 1. A rack comprising a bottom, wire bails

pivots connected one at each end of said bottom and adapted to fold under the same or to be extended vertically therefrom, each of said bails comprising spaced apart portions which connect with the bottom and extend therefrom for a distance and are then bent inwardly toward each other to make shoulders, thence formed with U-shaped recesses, and terminating in a handle portion a distance beyond said recesses, and an upper member detachably connected with said bails, resting at each end on the shoulders thereof and yieldingly retained in said recesses, said upper member having a plurality of compartment openings through which 70 jars or like articles which rest on the bottom may pass, substantially as described.

2. A rack comprising a bottom, wire bails pivots connected one at each end of said bottom and adapted to fold under the same or to be extended vertically therefrom, each of said bails having a recess in a side thereof and a shoulder below each recess, and an upper member provided with means at each end to engage with the bails, said means 80 passing over the bails detachably seating in the recesses in the sides of said bails and resting on said shoulders, said upper member having a plurality of compartment 85 openings through which jars or like articles adapted to rest on the bottom may pass, substantially as described, and resilient means carried by the bails and arranged to engage the said bottom for urging the bails outward when the latter are in an upright 90 position.

3. A rack comprising a bottom including an outer frame and longitudinal and transverse members all formed of wire, two of 105 said longitudinal members at each end being formed into a loop, a wire bail pivotally connected to said loops at each end of the bottom, each of said bails having an inwardly bent recess in each side member thereof located a distance from the bottom, and an upper member for the rack composed of an outer wire frame, a plurality of transverse wires and a longitudinal central wire and means at each end to pass over 110 each bail to engage therewith and seat in said recesses in the bails, substantially as described.

4. A rack comprising a bottom, handle members at each end of the bottom, a rack member comprising an outer frame of wire having parallel sides and ends, a wire member connected to and paralleling each end of the frame which is spaced a short distance therefrom to receive the handle members between the wire members and the ends of the outer frame, a plurality of transverse wires slidably mounted on the sides of the frame to vary the size and position of the spaces between them and a central longitudinal wire with which the transverse 125 130

wires are adapted to adjustably engage in any position in which they may be adjusted.

5. A rack comprising a bottom, handle members one at each end of the bottom, a
6. rack member comprising an outer frame of
wire having parallel sides and ends, a wire
member connected to and paralleling each
end of the frame which is spaced a short
distance therefrom and on the inner side
10 thereof to receive the handle members be-
tween the wire members and the ends of the
outer frame, a longitudinal wire connecting
said wire members and formed with a plu-
rality of corrugations in the length thereof,
15 and a plurality of transverse wires slidably
connected at their ends to the sides of the

frame and adapted to adjustably engage
with said longitudinal wire to vary the size
and position of the spaces between them,
seated in the depressions formed by the 20
corrugations.

6. A rack comprising a supporting mem-
ber, and a superposed retaining frame, said
frame comprising a border member, a longi-
tudinal corrugated member and a plurality 25
of transverse members, said transverse mem-
bers being supported by said border mem-
ber, adjustable in position, and held in ad-
justed positions by said corrugated member.

In testimony whereof I affix my signature.

PETER D. PEARCE.
